Patented Oct. 22, 1918.

UNITED STATES PATENT OFFICE.

HENRY C. EGERTON, OF RIDGEWOOD, NEW JERSEY.

SHOE.

1,282,399.

Specification of Letters Patent. Patented Oct. 22, 1918.

Application filed July 11, 1918. Serial No. 244,340.

To all whom it may concern:

Be it known that I, HENRY C. EGERTON, a citizen of the United States, and now resident of Ridgewood, county of Bergen, and 5 State of New Jersey, have made a certain new and useful Invention Relating to Shoes, of which the following is a specification, taken in connection with the accompanying drawing, which forms part of the same.

10 This application is a continuation in part of my co-pending applications Serial No. 218,679, filed February 23, 1918, Serial No. 233,000, filed May 7, 1918, Serial No. 235,078, filed May 17, 1918, and Serial No. 239,514, 15 filed June 12, 1918, that is, this case contains subject-matter taken therefrom.

This invention relates especially to boots and shoes comprising stiffening or connecting elements containing cloth or other 20 fibrous material coated or impregnated with cured phenolic condensation cementing material, that is, phenol aldehyde products, such as bakelite, condensite or the like. Shoe stiffening members of canvas or similar 25 fabric impregnated with such phenolic condensation cementing material and having one or more layers cemented together and more or less cured or solidified may be incorporated in this way and toe boxes, 30 counters and stiffening inner soles of this construction may be advantageously used in various types of shoe and boot construction, either in connection with leather, canvas or rubber shoe types. These shoe stiffening 35 members may be formed or arched up into the desired shape and then cured so as to produce shaped stiffener members which retain their form and stiffen and support the other parts of the shoe when connected 40 therewith in any suitable way.

In the accompanying drawings showing in a somewhat diagrammatic way illustrative embodiments of this invention,

Figure 1 is a longitudinal section showing 45 in separated position the parts which may be used to form a shoe of this general character.

Fig. 2 is a partial longitudinal section through a completed shoe of this type.

50 Fig. 3 is a longitudinal section showing another form of stiffened shoe sole including the heel.

Fig. 4 is a transverse section showing a sole stiffener.

Fig. 5 is a transverse section through a 55 rubber shoe sole with which such a stiffener may be used.

Fig. 6 is a transverse section through another shoe sole construction comprising such an incorporated stiffener.

Fig. 7 is a transverse section showing still 60 another stiffened shoe sole; and

Figs. 8 and 9 are transverse sections through other sole constructions.

In the illustrative arrangement shown in Fig. 1, the shoe may comprise the usual shoe 65 elements including the upper 1 of any suitable material, such as waterproofed or coated canvas, for instance, may be reinforced adjacent the toe by a toe box formed of one or more thicknesses of heavy canvas 70 or other fabric impregnated with phenolic condensation cementing material which may be cured at suitable heat for sufficient time to convert it into the solid permanent form throughout at least a considerable part of 75 the toe box, the lower edges below about the point 7, where if desired, the material may have only a single thickness, being left in partly cured soft condition in which it is much more flexible and readily cemented 80 to other phenolic impregnated elements. The upper part may, if desired, comprise several thicknesses of impregnated canvas or the like, such as 5, 6, to give ample strength and stiffness and the toe box may 85 be covered by a toe cap 2 of any suitable material, such as coated or waterproofed canvas, if desired. A similarly impregnated and stiffened counter or heel stiffening member may be formed of a plurality of layers 90

95, 96 of phenolic impregnated canvas which may be cured in the upper part into the solid strong condition usually known as the moderate curing of such material, so as to retain the desired shape permanently 95 while the lower part of this counter below about the point 22 may be formed of a single thickness of material which may for some purposes be advantageously left in the soft or partly cured condition. In last- 100 ing the shoe the upper, toe box, toe cap and counter may, for example, be stitched to the in-sole 11 of any suitable construction

which may advantageously be formed of one or more layers of heavy fabric or canvas coated or impregnated with similar phenolic condensation cementing material which may 5 be left in soft or uncured condition so that the parts may be bent readily and the edge 10 fin or portion bent down and inward to form an attaching flange 14 through which the lasting stitches may be secured along 15 the lines 15 at the back of the shoe and along the dotted lines 10 at the toe. These 20 toe box and counter stiffener members are described and specifically claimed in my copending application, Serial No. 233,000, 25 filed May 7, 1918. If desired, also, a welt strip, such as 8, of similarly impregnated heavy canvas or braided fabric, may be 30 sewed into the front of the shoe by this lasting stitching and the welt strip may of course extend around the shoe about as far as the heel front as in ordinary leather shoe 35 construction. The sole may be efficiently strengthened by incorporating therein a number of layers of such phenolic impregnated paper, cloth or other suitable material, preferably of a more or less fibrous character, and for instance a filler strip 16 of this material may be applied next the in-sole 11 and one or more other stiffening 40 strips 17, 18 of generally similar character also applied in so far as desirable to further stiffen the shank portion of the sole. A sole connector strip 19 which may extend 45 throughout substantially the entire area of the shoe sole may then be applied so as to be in contact with these inner layers or elements and to engage the inturned portions or edges of the lasted upper shoe elements. These sole layers or elements may all be 50 securely and permanently united by compressing the parts and simultaneously curing or solidifying them by the necessary heat maintained for sufficient time to convert the phenolic condensation cementing material with which they are impregnated into the desired solid stiff form. The welt strip under these conditions may, of course, be compressed against the sole connector strip 19, as shown in Fig. 2, and this may 55 leave a projecting edge of this sole connector to which a leather or other sole may be attached in any suitable way as by stitching extending substantially along the line 9—9 around these elements.

60 It is sometimes advantageous, however, to simultaneously connect a rubber composition sole, such as 20, which may have the integral heel 21, to the other parts at the same time that the various phenolic condensation cementing material is cured. For 65 this purpose it is usually desirable to have the sole connector 19 provided with a layer or coating of frictioned rubber composition which may be worked into the coarsely woven canvas or other fabric before it is

impregnated or coated on its other side with the phenolic condensation material, such as bakelite varnish, although of course in some cases it may be desirable to simultaneously apply the frictioned or other rubber coating to one side of the fabric and the phenolic condensation cementing material to the other. Where a rubber heel is to be attached in this way it is desirable to provide suitable interlocking connecting members, such as the heel rivets 23, 24, which may extend up through the in-sole elements and be headed over inside of the same and have projecting headed portions to enter the rubber heel and interlock therewith during the vulcanizing process so as to insure permanent connection under the hard service conditions to which they are liable. It is also desirable to have a cemented liner strip, such as 13, cover these rivets and be cemented in place to the other in-sole elements during the curing and vulcanizing process which takes place in suitably heated molds capable of holding parts together and exerting thereon the desired degree of compression.

The curing of the bakelite or other phenolic condensation cementing material may be carried out at varying temperatures and complete curing can in most cases where 95 relatively thin layers or blocks are being treated be effected in half an hour or an hour or so at temperatures around 300 degrees Fahrenheit. This corresponds quite closely with the vulcanizing temperatures of 100 rubber sole composition commercially used which can of course be regulated by the incorporation of different proportions of various accelerators or special vulcanizing agents and as well known the time of 105 vulcanizing of these compositions can be retarded when desired by the incorporation of more of the inert weighting or mineral loading materials. In this way a single heat treatment under pressure may be used to 110 vulcanize in place the rubber sole with or without the heel of the shoe and to permanently unite and shape up the sole reinforcing and connecting cementing material of 115 this general character.

In the form of the invention shown in Fig. 3 the sole connector stiffener strip or member 27 may, if desired, have its lower surface coated with any suitable rubber composition 93 which may in some cases be 120 frictioned thereto either before or simultaneously with the application of the phenolic condensation cementing material to the other side of the strip or canvas member preferably so as to impregnate its fibers to a considerable extent at least. In case the sole connector does not have sufficient thickness and stiffness when cured an additional stiffening strip or layer 26 which may have 125 phenolic condensation cementing material 130

applied to or incorporated therewith may also be used and in some cases an additional layer of impregnated or other fabric 28 may be interposed or otherwise incorporated as 5 an additional shank stiffener, as shown in Fig. 3. In some cases it is desirable to more or less unite and shape or arch up these fabric stiffener members before they are united to the rubber shoe sole and for this 10 purpose they may be molded under pressure at sufficient heat to more or less cure them and solidify the incorporated phenolic condensation cementing material and if this is done at moderate temperatures of, say, 200° 15 Fahrenheit or less for a number of hours these stiffening elements may, if desired, be completely cured or solidified without undesirably vulcanizing or altering the rubber layer or composition which may be present 20 on the lower side of the sole connector 27. During the shaping and molding of such impregnated fabric stiffeners which if desired may be effected without the complete curing thereof it is in many cases desirable 25 to squeeze out a considerable or the major part of the phenolic condensation cementing material from the attaching edge portions of the stiffener elements as by compressing the same considerably more forcibly than 30 the other parts of the stiffening members. For instance, these impregnated fabric strips may be preliminarily compressed in a cool or moderately heated mold so that the attaching edge portions 29, 30 may sometimes as indicated be reduced to even less 35 than half of the thickness of the rest of the strips, if desired, while the adjacent portions 32 may be of gradually increasing thickness as indicated. In this way when 40 the material is finally cured these attaching edge portions are relatively soft and yielding and are much more readily stitched or nailed to the shoe welt, leather or other sole or other parts than if they contained 40 or 45 50 per cent of cured phenolic condensation cementing material. It is of course understood that similar results can be secured by applying in the first instance a relatively small proportion of such bakelite varnish or 50 other suitable phenolic condensation material to these attaching edge portions of these stiffening elements and in such event all of the parts can be assembled and molded together with the rubber composition shoe 55 sole in the vulcanizing molds. As indicated the shoe sole 25 of any suitable rubber composition may if desired, have the heel portion 31 and may be forced in the vulcanizing mold against the rubber coated side 93 60 of the sole connector so that when subjected to the curing and vulcanizing heat the sole is vulcanized and simultaneously united to the sole connector and the phenolic condensation cementing material is simultaneously 65 cured preferably to the moderately cured

solidified condition so as to have the stiffness, strength, waterproof properties and also the smooth upper surface desired, which can, of course, be secured in any of these forms of shoe sole by giving the coöperating mold 70 element a smooth or polished surface. This form of stiffened sole construction is described and more specifically claimed in my co-pending application, Serial No. 235,078, filed May 17, 1918. 75

Fig. 4 shows still another arrangement in which the stiffener member is indicated as comprising one or more layers 33, 34 of canvas or other suitable material which may be coated or impregnated with phenolic condensation cementing material and then cured into stiff, permanent form in which the two layers are strongly and permanently united and also shaped or arched up if desired. 80 The use of one or more such fabric stiffener strips or elements containing cured phenolic condensation material permanently incorporated and united with or otherwise used in connection with a rubber or other sole is quite advantageous in many cases, since the 85 rubber or other flexible sole may be given in this way sufficient additional strength or stiffness so that when the wearer is walking over a stony or other uneven surface the shoe sole is not objectionably bent or indented, and if desired such stiffened rubber soles may be thus given fully as much 90 strength and stiffness as if formed entirely of high grade sole leather without sacrificing the desirable tough and other serviceable characteristics of a relatively pure rubber composition which are usually desirable in the wearing surface of the sole. Any desired number of coated or impregnated 95 fabric strips or members may be used for 100 such stiffening, strengthening purposes and heavy fabric of any suitable character, such, for instance, as canvas may be used and may advantageously be thoroughly impregnated so that when compressed and cured it may 105 contain some thirty to sixty per cent. more or less of bakelite varnish or other suitable phenolic condensation cementing material. Good results in making such sole stiffening members in this way may be secured by thoroughly impregnating or filling heavy canvas 110 with No. 1 bakelite varnish as by repeatedly immersing the canvas therein and running it through pressure rolls. Two plies of heavy cotton duck are usually sufficient for 115 general purposes when something equivalent to eight ounce army duck is used for these two layers. They may be thoroughly and strongly united by first impregnating them with phenolic condensation cementing 120 material of this character and then curing or uniting them by heat after they have been forced directly together so as to preferably give what is known as the intermediate curing or hardening of such phenolic ce- 125 130

menting material, as is known as bakelite varnish. Good results can usually be secured by curing such material under pressure at temperatures of about 300° or so Fahrenheit for an hour or so, and when two such layers of duck are cured in this way they can be thoroughly united into a quite smooth, hard, strong sheet about $\frac{1}{16}$ th of an inch thick which contains some fifty per cent. by weight of the cured phenolic condensation cementing material. The resistance of such a compound sheet stiffening element a sixteenth of an inch thick can be appreciated by considering that a relatively narrow strip can be bent from a straight form into a circle of two or three inches diameter without serious cracking or injury, and also that the bending modulus of rupture thereof corresponds to 15,000 to 18,000 pounds or so per square inch. Cured phenolic condensation stiffening elements with or without one or more layers of cloth, paper or other fibrous material are permanently stiff and strong and are practically waterproof and impervious and also independent of any ordinary heat changes to which footwear is properly subjected which is in marked contrast to the softening of pyroxylin or similar cementing material when moderately heated and its tendency to crack when chilled. A stiffening element of this general character consisting of or comprising a sheet or layer of cured phenolic condensation cementing material when used in a shoe sole above a rubber sole or element therein and preferably incorporated with such rubber sole element can effectively prevent the undesirable action of the rubber composition on the foot of the wearer so as to remove this objection to ordinary rubber shoe soles. Fig. 5 indicates a way in which such a sole stiffening member may be used in connection with a rubber shoe sole 36 without vulcanizing or otherwise permanently uniting it thereto. The shoe sole may as indicated be molded with a recess 37 to accommodate the stiffener member and the sides 35 of this stiffener recess may be arranged adjacent thereto and preferably close enough to the edges of the stiffener so that when the sole is stitched or otherwise secured to the shoe, portions of the rubber are forced over toward the stiffener to hold it in lateral alinement at least sufficiently to prevent any undesirable cutting, wearing or other action on the stitching, for instance. Fig. 6 shows another arrangement in which a similar sole stiffener which may of course be shaped or arched up before curing and outlined or cut to the desired shape may be used in connection with a shoe sole of the standard Goodyear welt type. The upper 44 of the shoe, together with the lining 43 if desired, may be stitched to the in-sole 38 and to the welt strip 48, thus leaving a space below the in-

sole in which the sole stiffener consisting of one or more united layers or strips of canvas or other fabric 33, 34, may be arranged together with cork or other filling composition which is preferably arranged around the edges of the stiffener as at 62 to substantially maintain its lateral alinement under service conditions. The leather, rubber or other sole 41 may be stitched or otherwise attached to the welt strip 48 as by the stitching 42 and the stiffness of the sole is of course greatly enhanced by the reinforcing action of these stiffener elements. Fig. 7 shows still another construction in which the in-sole 46 is attached to the upper and lining strips 43, 44 and to the welt strip 48, the space below the in-sole being in this instance filled with the usual cork or other filling in-sole composition 47. The sole stiffener preferably comprising fibrous material, such as one or more layers of canvas or other fabric coated or impregnated with phenolic condensation cementing material and cured or hardened under heat in the desired shape may as indicated in this instance extend throughout the entire width of the shoe sole so that the edges of the united stiffener layers 33', 34' may be visible at the edges of the finished shoe sole. The stiffener may be outlined or cut to shape before assembly with the other parts of this shoe or trimmed or ground off thereafter so as to be in line with the other shoe sole portions. This stiffener member may be united to the other elements of the shoe when it is assembled by any suitable means and as indicated the stiffener, welt and leather or other shoe sole 45 may be securely attached together by nailing, stapling or stitching, or by the screw nails 47 which may be forced through these parts in the usual way to hold them securely in position during service.

In the embodiment of the invention shown in Fig. 8 one or more fabric strips or stiffener members 50, 52 coated or impregnated with phenolic condensation cementing material may be used and if desired an interposed or uniting strip or member 51 of special open mesh or loosely woven fabric, if desired, may be used in contact with or interposed between such stiffening strips. In some cases it is sufficient where such an open mesh strip is interposed between two previously impregnated stiffening elements to rely upon the phenolic condensation cementing material which may be squeezed into this connector strip during the molding and curing process without applying any such cementing material directly thereto. This uniting stiffener strip may, if desired, have an edge portion 53 extending into or through the adjacent attaching or edge portion 60 of the rubber shoe sole 49 and this part of the strip may have the rubber securely incorporated with

or attached thereto during the vulcanizing process in connection with a previously applied layer or coating of any suitable rubber composition which this part of the connector strip may contain. If desired, a frictioned or other rubber coating 93 may be applied to the lower surface of the stiffening strip or element 52 with which the rubber sole engages and this is preferably done before the phenolic condensation cementing material is applied to this strip or layer of fabric. In some cases it is, however, sufficient to impregnate the fabric with phenolic condensation cementing material in the usual way and after drying force the uncured rubber sole composition against the strip in the vulcanizing mold when the heat first softens or melts the phenolic condensation cementing material to such extent that it is forced to some extent out of the fabric with which the rubber engages and the softened rubber composition is simultaneously forced into the pores or interstices of the adjacent fabric so as to secure strong adherence thereto when the vulcanizing is completed. Fig. 9 shows still another arrangement in which several layers of canvas or other fabric 55, 56 impregnated or coated with phenolic condensation cementing material may be preliminarily stitched at 61 and united to form the stiffener and having undercut edge portions formed by the projecting portions 92 of the lower layer 58 of such material. Other interlocking portions of the stiffener may be conveniently formed by cutting or bending down flaps or portions 58, 59 which may be first cut along H shaped lines and then forced downward during the molding and curing of the stiffener, for example, so as to be permanently retained in this general shape. During the molding and vulcanizing of the rubber sole 49 thereto portions or plugs of rubber 57 may be placed in these openings or forced thereinto during the molding and vulcanizing process so as to form interlocking securing plugs or rivet members 36 of rubber definitely positioning this part of the stiffener with respect to the coöperating part of the shoe sole without leaving any very large or undesirable amount of rubber exposed on the upper surface of the sole element. These constructions of Figs. 8 and 9 are described and more specifically claimed in my co-pending application, Serial No. 239,514, filed June 12, 1918. Of course many of the preceding forms of stiffener comprising one or more layers of canvas or other fabric carrying phenolic condensation cementing material may be sold or shipped in cured or uncured form, the layers being preferably at least adhesively secured in proper position or slightly tacked or stitched together as by the stitching 61 shown in Fig. 9; or they

may be assembled in uncured condition in the vulcanizing mold together with the rubber sole composition, and then during the heat of the vulcanizing process and pressure of the mold the parts may all be forced together and the rubber vulcanized and interlocked and united with the stiffener elements which are permanently stiffened and united by the curing of the incorporated bakelite or other phenolic condensation cementing material. In this way it is possible to coat or impregnate such fabric stiffening sheets or elements and supply them in uncured condition, if desired, to rubber shoe sole manufacturers for incorporation in any desired part of the rubber soles in which their edge portions at least are preferably more or less embedded and interlocked. Where the separate cured stiffeners are sold or shipped separately before being attached to the rubber shoe soles or other parts of the shoe they may of course be united to the coöperating shoe elements in any suitable way as by cementing, stitching or nailing, relatively yieldable penetrable edge attaching portions being desirable for this purpose which may be thinner or contain less phenolic condensation material, for example. In some cases certain rubber compositions seem to become more or less impregnated with the aldehyde component of the bakelite or the like so as to cause a noticeable odor, which gradually disappears, and if desired, this odor can be more rapidly eliminated or destroyed by moderate heating to temperatures insufficient to injure or alter the rubber or phenolic condensation cementing material, several days exposure to the air at heats of 100° to 120° F. or so being ample to practically or completely destroy any objectionable odor.

This invention has been described in connection with a number of illustrative embodiments, forms, proportions, elements, parts, shapes, materials, compositions, methods of preparation, production and use, to the details of which disclosure the invention is not of course to be limited, since what is claimed as new and what is desired to be secured by Letters Patent is set forth in the appended claims:

1. The shaped up shoe stiffener member comprising a plurality of layers of canvas united by and thoroughly impregnated with cured phenolic condensation cementing material to the extent of about 30 to 60 per cent. by weight of said stiffener member and strengthening the same.
2. The shoe stiffener member comprising a plurality of layers of fabric united by and impregnated with cured phenolic condensation material to the extent of more than 25 per cent. by weight of said stiffener member.
3. The arched upstiffening shoe element

- comprising fibrous material and incorporated cured phenolic condensation cementing and stiffening material.
4. The stiffening shoe element comprising 5 cotton fabric impregnated with cured phenolic condensation cementing and stiffening material, said stiffening element comprising a vulcanized rubber portion engaging and permanently secured to said fabric.
- 10 5. The shoe stiffener member comprising fibrous material carrying phenolic condensation cementing material.
6. The shoe element comprising porous material carrying cured phenolic condensation cementing material to stiffen and strengthen the same.
- 15 7. The shoe element comprising fibrous material carrying cured phenolic condensation cementing and stiffening material, said 20 shoe element comprising a vulcanized rubber portion vulcanized to said fibrous material.
8. The shoe stiffener element comprising fibrous material and incorporated cured phenolic condensation cementing and stiffening 25 material.
9. The arched up shoe stiffener member comprising a plurality of layers of fabric containing cured phenolic condensation material to the extent of about thirty to sixty 30 per cent. by weight of said stiffener member and stiffening and strengthening said member.
10. The shoe stiffener member comprising fabric containing phenolic condensation material to the extent of about thirty to sixty 35 per cent. by weight of said stiffener member for stiffening and strengthening said member.
11. The shoe sole stiffener member comprising 40 fabric containing cured phenolic condensation cementing material and having a previously shaped portion adapted to stiffen and strengthen the coöperating shoe elements with which said stiffener member is incorporated.
12. The shoe stiffener member comprising 45 fibrous material containing cured phenolic condensation cementing material adapted to stiffen and strengthen the coöperating shoe elements with which said stiffener member is used.
13. The shoe sole stiffener member formed 50 of a plurality of layers of fabric containing cured phenolic condensation cementing material and having relatively thinner more penetrable attaching edge portions containing less of said cementing material and adapted to be more readily penetrated by the attaching stitching.
- 60 14. The shoe sole stiffener member formed of fabric containing phenolic condensation cementing material and having relatively penetrable attaching edge portions containing less of said cementing material.

15. The stiffener member adapted to co- 65 operate with a shoe element and comprising a plurality of layers of canvas carrying cured phenolic condensation cementing material uniting and strengthening said stiffener member, portions of said stiffener member being relatively flexible and adapted to promote the union of said stiffener member with the coöperating shoe element.
16. The stiffener member adapted to co- 70 operate with a shoe element and comprising 75 fabric carrying phenolic condensation cementing material uniting and strengthening said stiffener member, edge portions of said stiffener member being relatively penetrable and adapted to promote the union of 80 said stiffener member with the coöperating shoe element.
17. The stiffener member adapted to co- 85 operate with a shoe element and comprising 85 fibrous material carrying phenolic condensation cementing material for strengthening said stiffener member, portions of said stiffener being relatively thinner and more penetrable and adapted to promote the union 90 of said stiffener member with the coöperating shoe element.
18. The shoe sole stiffener member comprising a plurality of heavy fabric layers carrying cured phenolic condensation cementing material to stiffen, waterproof and 95 unite said member, said stiffener member having a relatively thin attaching edge portion extending around its front portion and a rubber coating on one side of said stiffener member.
19. The shaped up shoe stiffener member comprising a plurality of heavy fabric layers carrying cured phenolic condensation cementing material to stiffen and strengthen 105 said member and give it a substantially smooth surface.
20. The fabric shoe stiffener member impregnated with phenolic condensation cementing material to stiffen and waterproof 110 said member and a rubber coating on portions of said stiffener member.
21. The fibrous shoe sole stiffener member having substantially the outline of a 115 shoe sole and carrying cured phenolic condensation cementing material.
22. The shoe sole stiffening member comprising a plurality of layers of fabric carrying phenolic condensation cementing material which is cured at least throughout portions of said member to stiffen and maintain 120 the shape thereof.
23. The shoe stiffening member comprising 125 fabric carrying phenolic condensation cementing material which is cured and solidified at least throughout the body portions of said member to stiffen and maintain the shape thereof.
24. The shoe stiffening member comprising

ing fibrous material containing phenolic condensation cementing material which is cured at least throughout portions of said member to stiffen and maintain the shape thereof, the attaching portions of said member being relatively weaker and more readily penetrable by attaching devices.

25. The shoe stiffener member comprising fabric containing phenolic condensation cementing material and having a coating of 10 rubber composition adhering to the fabric throughout a portion of said stiffener member.

HENRY C. EGERTON.
